Attorney.

UNITED STATES PATENT OFFICE.

ARMAND CHARLES FREY, OF SOULTZ, FRANCE.

VISCOSE-DISTRIBUTING DEVICE FOR ARTIFICIAL-SILK PLANTS.

Application filed March 30, 1927, Serial No. 179 679, and in Switzerland March 31, 1926.

In devices used for the manufacture of artificial silk, the viscose is fed to the spinning nozzles either by means of ordinary pumps or by toothwheel-acting pumps intended for adjusting the amount of viscose to the required quantity that should be delivered.

The present invention has for its object a viscose-distributing device designed after the known principle of the toothwheel-acting pump, that is to say, the viscose flowing under pressure is fed to one side of the teeth of said wheels wherfrom it is next passed in determined quantities to the other side, to be then transmitted to the spinning nozzles.

The backlash in these parts on account of their unavoidable wear, is eliminated, in most devices, through the provision, either for one of the toothwheels or for both, of a crescent-shaped distance-piece inserted between the teeth of the wheel and the inner wall of the pump casing, said distance-piece being continuously acted upon by an elastic pressure tending to force it between the wheel periphery and the casing wall.

Now, all of these devices are subject to a drawback in that they allow of no actual regulation in view of increasing or reducing the quantity of viscose to be fed; after all the result aimed at lies in automatically eliminating said backlash due to wear of the parts. As, furthermore, the distance-piece thus introduced between the toothwheel and the housing wall uninterruptedly exerts a braking action between them, these devices are subject to a rather considerable wear at these points, on account of which they cannot serve the purpose after a certain time of working.

The present device is free of any such drawback. It comprises the employment of a crescent-shaped distance-piece likewise intended for avoiding the gap due to play or backlash of the parts as a result of wear, but so arranged that said gap, and, therefore, the amount of viscose fed on, can be, at will, either reduced or amplified, according to whether said viscose is in a more or less diluted state. Adjustment of the feed is operated from outside and can be effected

with the accuracy required for bringing the quantity of viscose up or down to any predetermined rate of delivery.

The object of this invention has been shown, by way of example, in the accompanying drawings, wherein:

Fig. 1 is a longitudinal section of the device;

Fig. 2 a sectional view through the central part wherein the two toothed wheels are located;

Fig. 3, a side view, in the assumption of a removal of the cover; and

Figs. 4 and 5 show said cover, by a side and a plan view respectively.

The two spur-wheels 4 and 5 are enclosed in a housing made of three parts, say a flanged bearing 1, a central member 2 and a cover 3. Said toothed wheels mesh in one another free of any gap, and they are so exactly executed as to cause wheel 4 to come in contact with the surrounding housing wall of the middle member 2 subject to no play whatever. As to wheel 5, which, as can be seen, is not guided by a shaft, it is lodged eccentrically inside the cylindrical recess 6 hollowed out of the crescent-shaped member 7, which is movably located in a corresponding recess 8 of the central member 2. It will be readily understood that any rotatory move of said crescent-shaped member 7 will bring about, due to the eccentric position of wheel 5, an interval of play not only between the teeth of the two wheels, but likewise between the wheel 5 and the inner cylindrical wall of recess 6; and that, by rendering the gap wider or narrower, an exact regulation of its width will be possible.

Regulation of this gap will be accomplished by means of the peg 9, which is rotatably mounted in the cover 3, and is provided with an eccentric stud 10 at its inner end, this stud 10 to enter as a tenon in the slit 11 provided inside the crescent-shaped plate 7, thus allowing to have said plate 7 moved on or back whenever the head 12 of peg 9 is turned one way or the other.

A graduated scale 13 has been provided upon the head 12 of said regulating peg 9 whereby it is possible to adjust its position

with respect to a mark 14 branded on the cover 3; besides, a set-screw 15 serves to fix said peg 9 in the position it has been thus given.

5 The wheel 4 is driven by the worm-wheel 16 fixed upon the shaft 17 which latter is connected with the shaft 19 of toothwheel 4 by means of a coupling 18.

The viscose fed under pressure will enter 10 at 20 into the device and will thus arrive, through opening 21, within reach of the spur wheels 4 and 5 which will drive it to the opening 22 wherefrom it will be led through the opening 23 to the spinning nozzles.

15 If, for any reason, such as wear of the movable parts, the amount to be fed must be modified, it will be sufficient to unscrew the set screw 15 and to turn the head 12 one way or the other so as to have it adjusted with respect to the mark 14, a regulating 20 operation which can be effected without ev-

er stopping work, and which requires but a few seconds.

I claim:

A gear wheel pump for distributing viscose in artificial silk plants comprising in combination: a casing; a positively driven spur wheel closely lodged in a cylindrical recess formed inside the casing; a second spur wheel meshing with said driven spur wheel, a crescent-shaped member in which said second spur wheel is eccentrically lodged; said crescent-shaped member being freely lodged in a circular recess inside said casing, and a peg rotatably mounted in the pump casing and ending with an eccentrically placed stud engaging a slit formed in the outer periphery of the crescent-shaped member, substantially as described.

In testimony whereof I signed hereunto 40 my name.

ARMAND CHARLES FREY.
